UNITED STATES PATENT OFFICE.

THOMAS McMONAGLE, OF AUGUSTA, MAINE.

SHAVING BRUSH.

Application filed September 15, 1921, Serial No. 500,761. Renewed October 14, 1922. Serial No. 594,646.

To all whom it may concern:

Be it known that I, THOMAS McMONAGLE, a citizen of the United States, residing at Augusta, in the county of Kennebec and State of Maine, have invented a new and useful Shaving Brush, of which the following is a specification.

This invention relates to shaving brush constructions, and more particularly to a shaving brush having novel means for heating water contained in the handle portion thereof to provide hot water for shaving purposes.

Another object of the invention is to provide means for forcing the heated water through the bristles or brush portion of the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a side elevational view of a brush constructed in accordance with the present invention.

Figure 2 is a vertical sectional view through the brush.

Referring to the drawing in detail, the handle portion 5 of the brush is hollow in formation, and in one end thereof is secured head 6 which supports the bristles 7 of the brush.

This head 6 is provided with an opening to accommodate the nozzle 8 which tapers toward the outer end thereof, and is provided with a plurality of openings to permit fluid to pass therefrom.

Positioned within the hollow handle portion 5, is a tubular member 9 that has its lower end positioned in the nozzle 8, the upper end thereof terminating in spaced relation with the removable cover 10 so that fluid may pass from the hollow handle por-

tion into the tubular member to feed the nozzle.

Supported within the hollow handle portion is a disk 11 which is provided with a central opening to accommodate the tubular member 9, and as shown this disk is of a diameter to closely engage the inner wall of the handle portion 5 to act as a plunger to force the fluid upwardly. Openings 12 are formed in the wall of the handle portion adjacent to the bristle end of the brush, the openings being elongated and extending to a point substantially intermediate the ends of the handle 5. Arms 13 have connection with the disk 11 and have right angled portions 14 extending through the openings to be engaged by the fingers of the operator to cause the disk 11 to be moved longitudinally of the handle portion for ejecting the fluid.

The handle 5 is provided with a threaded portion at the upper end thereof, which threaded portion accommodates the removable cap 14 which is formed with air openings 15, to permit air to pass to the space 75 between the cover 15 and removable cover 10, the space between the covers 10 and 15 providing a heating chamber to accommodate a suitable tablet such as solidified alcohol or the like, which may be ignited to heat the 80 water contained in the hollow handle 5.

In the use of the device, water is placed in the hollow handle portion, whereupon the cover 10 is positioned on the handle. A tablet as described is placed in the cap 14 85 and ignited. It follows that when the cap is replaced, on the handle portion, the heat from the tablet heats the water in the handle which may be forced to the bristles or brush portion by means of the disk 11.

Having thus described the invention, what is claimed as new is:—

A shaving brush including a hollow handle portion, bristles at one end of the handle portion, a tubular member extending 95 into the handle portion and adapted to discharge fluid into the bristles, a disk within the hollow handle portion and having an opening to accommodate the tubular member, said disk contacting with the inner walls 100

of the hollow handle portion, said handle portion having elongated openings, arms having connection with the disk and having right angled portions extending through the openings, said arms adapted to be moved longitudinally of the body portion to move the disk within the body portion to force fluid therefrom.

In testimony that I claim the foregoing as my own, I have hereto affixed my signature 10 in the presence of two witnesses.

THOMAS McMONAGLE.
